United States Patent Office.

ABRAM SCHENCK, OF OVID, MICHIGAN.

Letters Patent No. 71,796, dated December 3, 1867.

IMPROVEMENT IN GRAIN-SEPARATORS.

The Schedule referred to in these Letters Patent and making part of the same.

TO ALL WHOM IT MAY CONCERN:

Be it known that I, ABRAM SCHENCK, of the town of Ovid, in the county of Clinton, in the State of Michigan, have invented a new and improved Grain-Separator and Cleaner; and I do declare that the following is a true and accurate description thereof, reference being had to the accompanying drawings, and to the letters of reference marked thereon, and being a part of this specification.

Figure 1 is a perspective view of the separator and cleaner.

Figure 2 is a vertical sectional view of the same.

The same letters refer to similar parts in each figure.

This invention consists in combining with the fans a series of flues, hoppers, valves, and conductors, so arranged that the strong currents of air created in the flues by the operation of the fans will draw off and force through the conductors all impurities, such as chaff, cockle, tailings, &c.

To enable those skilled in the art to manufacture this machine, a description of its construction will now be given, special reference being called to the drawings, and letters of reference marked thereon.

A A, &c., is a proper frame to fasten the working parts of the machine. B B are cross-beams or timbers, provided with proper devices in which runs the fan-shaft C. E is a pulley on the lower end of the shaft C, and when attached by belting to power, gives motion to it. D D D are hubs attached to the shaft C, and to which are fastened, by proper arms, the wings I I I, &c., of the fans. H H H are wind-chests, within which the fans revolve. Leading from the hoppers M¹ M² M³ to the wind-chests H H H are the flues N N N, provided with valves G G G, which are to be raised or lowered at pleasure, or as the case may require. From the wind-chests H H H run the conductors O O O, provided with depressed boxes K K K for the purpose of catching any grain that may accidentally be drawn into the flues. These boxes are provided with hinged bottoms L L L, held in place by the cords and weights J J J. F is a general hopper, into which the grain to be operated upon is poured after the fans have been put in motion. The current of air created by the motion of the fans draws the foul and light stuff which it is desired to remove up through the upper flue to the wind-chest, whence it is ejected by the same current of air through the upper conductor. Should this air-current, which can be regulated by the valves G, &c., be too strong, and draw into the flues any valuable grain, after passing through the wind-chest, it will fall to the floor of the conductor, and drop into the depressed box attached thereto. When enough grain has accumulated in this depressed box to overcome the weight J, the valve-bottom L will open and discharge the grain. The middle and lower flues, wind-chests, fans, conductors, and boxes, with their attachments, repeat the operation described above until the grain is discharged at P thoroughly cleansed.

What I claim as my invention, and desire to secure by Letters Patent, is—

The combination of the frame A with the cross-beams B B, the shaft C, the hubs D D D, and the wings I I I of the fan, the pulley E, the hoppers F M¹ M² M³, the flues N N N, the conductors O O O, the depressed boxes K K K, the bottom valves L L L, the weights and cords J J J, and the valves G G G, or their equivalents, all arranged substantially as described for the purpose designed.

ABRAM SCHENCK.
